UNITED STATES PATENT OFFICE.

BERNARD S. D. S. MARTIN, OF MCPHERSON, KANSAS.

STORM-CURTAIN FOR BUGGIES.

SPECIFICATION forming part of Letters Patent No. 709,026, dated September 16, 1902.

Application filed February 19, 1902. Serial No. 94,707. (No model.)

To all whom it may concern:

Be it known that I, BERNARD S. D. S. MARTIN, a subject of the King of Great Britain, residing at McPherson, in the county of McPherson and State of Kansas, have invented certain new and useful Improvements in Storm-Curtains for Buggies, of which the following is a full and complete specification, such as will enable those skilled in the art to which it appertains to make and use the same.

The object of this invention is to provide an improved storm curtain or curtains for a buggy or similar vehicle and improved means for connecting the curtain or curtains with the buggy or vehicle; and with this and other objects in view the invention consists in a storm curtain or curtains and means for connecting the same with a buggy constructed as hereinafter described and claimed.

20 In the drawings forming part of this specification, in which the separate parts of my improvement are designated by the same reference characters in each of the views, Figure 1 is a view of the top of a buggy with one part of my improved curtain in position, the other being removed; Fig. 2, a side view thereof, showing one of the parts for holding the curtain in a different position; Fig. 3, a front view of a detail of the construction, part of which is shown in dotted lines; Fig. 4, a view at right angles to Fig. 3; Fig. 5, a front view of another detail of the construction, showing one of the side supports of the curtain or a part thereof; Fig. 6, a side view of an attaching screw or support and showing a part of the buggy-hood in dotted lines; Fig. 7, a side view of a part of the top of a buggy and showing, on an enlarged scale, one of the side attachments of the curtain; and Fig. 8 a side view of another detail of the construction.

40 In the practice of my invention I provide a storm-curtain which consists of two separate similar parts, and in Figs. 1 and 2 of the drawings I have shown a buggy body or bed *a*, provided with the usual hood *b* and with a dashboard *c*, and in the practice of my invention I connect with the top front portion of the hood two rotatable rods *d*, one of which is shown in full lines and the other in dotted lines in Fig. 1, and each of these rods is provided at its outer end with a downwardly-directed end member or arm *d*². In connecting the rods *d* with the hood of the buggy I

employ a central bracket *e*, a front view of which is given in Fig. 3 and a side view in Fig. 4, and this bracket is angular in form and is secured to the hood, as shown at *e*² in Fig. 4, and in the angle of this bracket is a central piece *f*, having end sockets *f*², into which the ends of the rods *d* are passed, and at the opposite sides of the bracket *e* I employ eye-screws *g*, which are open at one side, as shown at *g*², and the rods *d* are notched, so as to be passed into the eyes *g*³, and when thus passed into said eyes and turned they will remain therein, and said eye-screws are screwed into the front top portion of the hood, as indicated in Fig. 6. I have also shown at *b*² the front side rods of a buggy-hood, and these side rods *b*² are provided near their upper ends with sleeves or bearings *h*, and at each side are employed rods *h*², provided at their upper ends with inwardly and downwardly directed members *h*³, which are pivotally connected with the parts *d*² of the rods *d* at *h*⁴ and which are provided at their lower ends with horizontal heads *h*⁵, through which are passed screws or other devices *h*⁶, which bear on or are pivoted in the sleeves or bearings *h*. The rods *h*² are composed of two parts connected by a sleeve *h*⁷, and the connection between the separate parts of the rods *h*² and the sleeve *h*⁷ are preferably made by means of bayonet-joints, as shown in Fig. 8. The lower ends of the bottom members of the rods *h*² are provided each with a head *h*⁸, having a slot *h*⁹, adapted to fit over a corresponding pin *i*, one of which is employed at each side of the buggy-body and which forms an attachment for the said rods *b*² of the buggy-hood, and connected with said lower end of said side rods *h*² are hooks *j*², which are adapted to engage the top of the dashboard *c*, and these hooks are free to swing on the rods *h*².

Secured to the front of the bed or body of the buggy is a bracket or support *j*, having a central upwardly-directed member *j*², provided with main laterally-directed spring-arms *j*³ and above which are smaller or supplemental laterally-directed spring-arms *j*⁴, and the upwardly-directed member *j*² is also adapted to support a whip-socket *k*, as clearly shown in Fig. 1.

As hereinbefore stated, my improved storm-curtain consists of two similar parts, which in the drawings are designated by the refer-

ence character m , and in practice the edges of these separate parts of the curtain are preferably folded over the rods d and h and are secured thereto in any desired manner, 5 and said parts of the curtain are buttoned at their upper corners to the bracket or support e by means of a button e^3 , and said separate parts of the curtain are also provided at their lower ends with spiral springs or similar fastening devices m^2 , m^3 , and m^4 , connected, respectively, with the spring-arms j^1 and j^3 and with the sides of the body of the buggy, all as indicated in Figs. 1 and 2. The spring connecting device m^4 of each curtain is connected 10 with the lower rear corner thereof and is designed to hold the curtain closed, and in Fig. 2 of the drawings I have shown one of the rods h^2 swung outwardly, so as to permit a party to enter the buggy or leave the same, and in 15 this figure that part of the curtain which is in practice connected with the rod h^2 which is swung outwardly is not shown, the other part of the curtain being shown partly in full and partly in dotted lines. When one 20 side of the curtain is swung outwardly in order to permit a party to enter or leave the buggy, the rod h^2 is lifted and detached from the pin i and the lower end thereof is swung outwardly and the hook i^2 connected with the 25 top of the dashboard, after which the side rod h^2 may be swung backwardly again into the position shown in Fig. 7, and as thus constructed it will be seen that my improved 30 storm-curtain securely closes when in position the entire front space of the buggy-hood. The rods d are free to turn in their supports, and the rods h^2 may be lifted and swung outwardly and lifted and swung backwardly whenever desired, or either of said rods may 35 be so manipulated, and my invention is not limited to the means herein described for supporting the rods d or the rods h^2 , and any suitable construction may be employed for this purpose, the only object in this connection being to provide devices which will 40 permit of the manipulation of the rods h^2 , as hereinbefore described. Each member of the storm-curtain is also provided with a transparent panel n and with an opening n^2 , closed 45 by a flap, through which the lines may be passed. In practice I may also connect the 50 separate parts of the curtain with the corresponding rods d and h^2 in any desired manner, and I prefer to make this connection so 55 that the rods h^2 and d may be taken off with the curtain and folded up and placed under the buggy-seat when not in use.

Having thus fully described my invention, what I claim as new, and desire to secure by 60 Letters Patent, is—

1. The herein-described supports for a storm-curtain of a buggy comprising rotatable rods detachably connected with the front of the top of the hood of a buggy and provided with downwardly-directed end members, side rods provided at their upper ends with inwardly-directed members pivotally

connected with the end members of the rotatable rod and means for pivotally connecting the side rods with side members of the 70 buggy-hood, said side rods being also provided at their lower end with notches or recesses and hooks pivotally connected therewith, substantially as shown and described.

2. The herein-described supports for a 75 storm-curtain of a buggy comprising rotatable rods detachably connected with the front of the top of the hood of a buggy and provided with downwardly-directed end members, side rods provided at their upper ends 80 with inwardly-directed members pivotally connected with the end members of the rotatable rods, means for pivotally connecting the side rods with the side members of the buggy-hood, said side rods being also provided at their lower end with notches or recesses and hooks pivotally connected therewith, and spring-arms secured to the front of the body of the buggy and extending laterally in both directions, substantially as shown 85 and described.

3. A storm-curtain for buggies consisting of two separate similar parts and means connecting the same with the hood of a buggy, comprising rotatable rods d detachably connected with the top of the hood of the buggy, and provided with downwardly-curved end members, side rods h provided at their upper ends with inwardly-directed members pivotally connected with the end members of the 95 rods d and with means for connecting them with the side members at their buggy-hood, said side rods being also provided at their lower ends with notches or recesses and with pivoted hooks, substantially as shown and described.

4. A storm-curtain for buggies consisting of two separate similar parts and means for connecting the same with the hood of the buggy, comprising rotatable rods d detachably connected with the top of the hood of the buggy, and provided with downwardly-curved end members, side rods h pivotally connected with the end members of the rods d and with means for connecting them with the side members of the buggy-hood, said side rods being also provided at their lower end with notches or recesses and with pivoted hooks, and the front of the buggy being also provided with laterally-directed spring-arms and said separate parts of the storm-curtain being provided with attaching-springs which are adapted to be connected with said arms and with the side of the body of the buggy, substantially as shown and described. 101

In testimony that I claim the foregoing as my invention I have signed my name, in presence of the subscribing witnesses, this 11th day of February, 1902.

BERNARD S. D. S. MARTIN.
